UNITED STATES PATENT OFFICE.

THEODORE D. GRILEY, OF BALTIMORE, OHIO.

MEANS FOR RAISING AND LOWERING BEATER ROLLS.

Application filed January 5, 1921. Serial No. 435,085.

To all whom it may concern:

Be it known that I, THEODORE D. GRILEY, a citizen of the United States, residing at Baltimore, in the county of Franklin and 5 State of Ohio, have invented a certain new and useful Improvement in Means for Raising and Lowering Beater Rolls, of which the following is a specification.

The beater roll of a paper pulping machine is very heavy. It is necessary occasionally to elevate it from the knives, hand operated means being now commonly employed for that purpose. Such hand-worked means has been laborious and difficult to operate. It is an object of the present invention to provide improved means whereby such work may be done by the same power that drives the beater roll, there being provided a suitable clutch lever 10 to apply power either to elevate or lower the roll.

The invention is embodied in the example herein shown and described, the features of novelty being finally claimed.

25 In the accompanying drawings—

Figure 1 is a view in side elevation showing a beater equipped with the invention.

Fig. 2 is a view of the left hand end of the machine broken out through the middle.

30 Fig. 3 is a top plan view also broken out as shown in Fig. 2.

Fig. 4 is a sectional detail on a larger scale of the clutch mechanism employed.

The general construction of such rolls is 35 well understood by those skilled in the art. In the views 5 designates the shaft of the beater roll, said shaft being supported at each of its opposite ends in a lever 6 pivoted at 7 in suitable standards 8. Each of the 40 free ends of the levers has loosely attached to it a screw 9 provided with nut 10 said nut being suitably supported upon the top of the standard 8. Each nut 10 has its rim formed as a worm gear and such member can be appropriately called a worm gear nut. Extending across the end of the machine is a 45 rotatable shaft 11 equipped with worms 12 to engage the worm-gear nuts 10 so that when said shaft is turned the levers 6 and the beater roll carried thereby may be either 50 raised or lowered according to the direction in which said shaft is turned. The pitch of the worm gear nuts 10 and their operating worms 12 is such that the levers 6 are held in the position to which they are left when raised or lowered.

The beater roll shaft has an axial stud extension 5^a geared by suitable bevel gears in a housing 13 to an external solid square shaft 14. The rotatable shaft 11 has an extension 11^a upon which is mounted a housing 15 containing a reversing clutch mechanism. The reversing clutch mechanism includes two bevel gears 16 and 17 loose on said extension 11^a and an intermediate driver 18 turned by the solid portion 19^a of a hollow square shaft 19. The hollow square shaft 19 receives the aforesaid square shaft 14 so that when the beater roll is turned the bevel gears 16 and 17 are turned. Sliding 60 on the extension shaft 11^a but so as to turn therewith is a double clutch member 20 adapted to be moved from a neutral or disengaged position into operating engagement with either of the gears 16 or 17 to 65 thereby cause the rotation of the shaft 11 to raise or lower the beater roll as may be desired. The telescoping square shafts 14 and 19 compensate for differences in the distance between the axis of the beater roll 70 shaft and screws 9 when the levers 6 are moved, it being noted that when the roll is raised the shaft moves away from the screws 9 on an arc concentric with lever 75 pivots 7.

The clutch member 20 is shiftable by means of a hand lever 21 pivoted at 22 on the exterior of the housing, said lever actuating a sliding rod 23 to which is attached a fork or strap 24 engaging loosely an annular groove in said clutch member 20. The clutch member 20 is normally held in neutral position between the gears 16 and 17 by coil springs 25 between the clutch member and the said gears 16 and 17 respectively. 80 When, therefore, the clutch operating lever is released the clutch returns automatically to neutral position.

In practice the beater roll is driven by suitable power as for example by a belt applied to the pulley 26 on the shaft of the beater roll. When the roll is driven, as in pulping stock, the bevel gears 16 and 17 of the clutch mechanism are also driven, hence when it is desired to elevate the roll it is only necessary to move the clutch lever in the proper direction to cause it to engage the gear 16 or 17 and the shaft 11 to turn. When the desired elevation of the roll is reached the clutch lever is released from the hand. To lower the roll to grinding position the clutch lever is moved in the oppo- 95 100 105 110

site direction. It will be noted that with this mechanism the same power that is used to drive the roll is also utilized to raise and lower the roll.

5 The forms of the parts can be changed without departing from the gist of the invention as claimed.

What I claim is:

10 The combination with a beater roll and its shaft, a pair of levers supporting said shaft, screws connected with said levers,

worm gear nuts on said screws, a worm shaft having worms engaging said worm-gear nuts, and a telescopic shaft driven by the beater roll shaft for driving said worm shaft and nuts, the parts of said telescopic shaft sliding but not rotating with reference to each other when driven by the beater roll shaft, and a reversing clutch mechanism for operably connecting at will the telescopic shaft with the worm shaft. 15 20

THEODORE D. GRILEY.
